COMBINED FRY PAN AND LID THEREFOR

Frederick W. Becker, Mansfield, Ohio, assignor to Westinghouse Electric Corporation, a corporation of Pennsylvania

Filed Jan. 21, 1963, Ser. No. 73,239

Term of patent 14 years

(Cl. D44—1)

Fig. 1.

Fig. 2.

Fig. 3.

Fig. 4.

FIGURE 1 is a side elevational view of a combined fry pan and lid thereof embodying my invention;

FIG. 2 is a front elevational view thereof;

FIG. 3 is a top plan view thereof; and

FIG. 4 is a fragmentary horizontal sectional view of the structure shown in the lower right hand portion of FIG. 3, with the lid omitted.

The sides opposite to those shown in FIGS. 1 and 2, respectively, are similar in appearance to those shown in said respective figures.

The dominant features of my design reside in the parts shown in the full lines.

I claim:

The ornamental design for a combined fry pan and lid therefor, substantially as shown and described.
